UNITED STATES PATENT OFFICE.

AUGUSTE ARTHUR CAILLE, OF DETROIT, MICHIGAN.

COIN-CONTROLLED WEIGHING-MACHINE.

SPECIFICATION forming part of Letters Patent No. 792,694, dated June 20, 1905.

Application filed October 29, 1903. Serial No. 178,989.

To all whom it may concern:

Be it known that I, AUGUSTE ARTHUR CAILLE, a citizen of the United States, residing at Detroit, in the county of Wayne and State of Michigan, have invented certain new and useful Improvements in Coin-Controlled Weighing-Machines, of which the following is a specification, reference being had therein to the accompanying drawings.

10 The invention relates to coin-controlled weighing-machines; and it consists in certain features of construction, as will be hereinafter set forth.

In the drawings, Figure 1 is a perspective view of the machine with a portion of the casing broken away to show the mechanism therein. Fig. 2 is an enlarged perspective view of the mechanism within the casing.

15 A is a weighing-platform, B the base containing the platform-levers, and C a column or standard projecting upward from the base and carrying at its upper end the casing D enclosing the controlling mechanism and carrying the index dial or scale.

20 The mechanism within the base may be of any suitable scale construction, and is therefore not illustrated.

E is the steelyard-rod extending upward from the levers in the base within the column C.

25 F is a yoke-frame to which the steelyard-rod E is connected, and G is a dash-pot within the yoke having its piston H connected thereto and serving to retard the oscillations of the rod E. I is another yoke or cross-bar connected with the yoke-frame F, and J represents the weighing-springs connected to the yoke I and at their upper ends secured to bearings K on a framework L within the casing.

30 The weight-indicating mechanism comprises an index-hand M, which is adapted in the operation of the machine to travel to a position determined by the amount of weight on the platform. This index is, however, normally locked from operation and is only released upon the insertion of a coin. The mechanism for determining the movement of the index-hand when released comprises a movable arm N, which is actuated by connec-

tion with the steelyard-rod and forms a stop 50 for arresting the index-hand.

O is a pinion for actuating the arm N, which in turn is actuated by a rack P, connected at its lower end with a cross-bar I. Thus the vertical movement of the cross-bar I under the 55 actuation of the steelyard-rod will cause the rack P to rotate the pinion O and turn the stop-arm N to the position determined by the weight on the platform.

The index M is secured to an arm M', which 60 is journaled in the frame to be free to swing through a segment so as to carry the index in adjacency to the dial or scale M² bearing the weight-indications. The arm M' is preferably fulcrumed in axial alinement with the arm 65 N and pinion O, and, as shown, this is accomplished by sleeving the arm M' upon the rock-shaft O', carrying the pinion O' and arm N.

70 Q is a latch-arm secured to the arm M' and adapted to engage with a lug Q' on the frame, thereby holding the arm M' in its initial position—that is, where the index points to zero. The latch-arm Q extends into the path of the coin, which latter is inserted through a slot in the machine, and passes downward 75 through a chute R, through a slot in which the arm Q extends. Thus chute R continues downward beyond the latch-arm, and finally discharges in a receptacle R' for holding the coin.

75 The arm M' is released by the disengagement of the latch-arm Q from the lug Q', which is caused by the striking of the coin against said latch-arm. This will permit the arm M' to swing upon its axis until arrested by contact with the stop-arm N, which is arranged to always be in the path of a projecting finger 80 a on the arm M'. The arm M' is actuated by any suitable propelling device, such as weight S, attached to the flexible connection S', which 85 passes over the segment S', attached to the arm M'. This weight will actuate the arm M' when released, and to prevent too sudden movement the weight is preferably arranged within a dash-pot S³, containing oil or some suitable medium for retarding its movement. Thus whenever a weight on the platform has 90 moved the stop-arm N and the arm M' has

been released through the insertion of a coin the latter arm will be actuated by the weight S until it is arrested by the finger a striking against the arm N, in which position the correct weight upon the platform is indicated by the index M.

One of the objects of my invention is to provide a mechanism which is preferably free to move under the actuation of the weight on the platform, and after it has assumed its correct position will be locked from movement before the index completes its movement.

Another object is to prevent the insertion of the coin and the consequent release of the index until the weight is upon the platform and has actuated the stop-arm M, thereby giving time for the locking to occur before the index is arrested.

The locking mechanism may be of any suitable construction, but preferably comprises a friction-locking dog, which is normally held free from its co-operating member, but is thrown into locking position by the movement of the index-arm. In the construction shown, 25 P' is a plain rod or bar intermediate the rack P and the cross-bar I.

P² is a bifurcated bearing through which the rod P' passes, and P³ is a friction-dog arranged intermediate the furcations of the bearing P² and adapted to engage with the bearing P'. The dog P³ preferably engages with the groove in the bearing P², which positions one end of said dog while permitting of a limited oscillation of the opposite end. 35 The opposite end of the dog is extended to form an arm or lever P⁴, which at its outer end is provided with a weight P⁵, adapted to draw the dog downward into position to frictionally engage and lock with the rod P'. This locking is caused by reason of the fact that the aperture in the plate P³, which forms the dog, is but slightly greater in diameter than the rod P', so that while said rod is free to move when the plate P³ is in a plane at right 40 angles to the axis of the rod a slight inclination of the plate will cause the binding of the rod with the edges of the aperture.

To hold the dog normally in its releasing position, a link T is attached to the extension 50 P⁴ of the dog and the upper end of this link is connected with a rock-arm T¹, and this rock-arm is pivoted on the frame and extends in horizontal direction. T² is another rock-arm connected with the rock-arm T¹ and extending vertically, so as to form a bell-crank lever. The rock-arm T² is connected by a link 55 T⁴ with the rock-arm T⁵ on the frame and the latter carries an antifriction-roll T⁶ for engaging with the cam S⁴ on the segment S².

60 The mechanism just described is such that the movement of the segment S², caused by the swinging of the arm M' when released by the actuation of the coin will cause the cam S⁴ to move in relation to the rock-arm T⁵.

65 As the rock-arm T⁵ normally bears against

the cam with its antifriction-roll T⁶ it is evident that a movement of the cam will cause a corresponding movement of the rock-arm, which, through the link T⁴, rock-arms T³ and T², and link T, will cause the lowering of the latter, permitting the lowering of the arm P⁴, which will tilt the dog P³ and cause it to engage with the rod P'. Thus the locking of the rod P' only occurs after the movement of the segment S², which latter being connected 75 with the arm M' is held stationary until said arm is released by the coin. In the locked position of the arm M' the cam S⁴ will hold the arm T⁵ in such a position that the intermediate mechanism will support the arm P⁴ 80 and hold the dog P³ in releasing position.

The insertion of the coin in the slot before the weight is upon the platform is prevented by a guard U, which in normal position extends into a slot U' in the coin-chute near the 85 upper end thereof and interrupts the path of the coin. This guard is actuated by mechanism controlled by the movement of the weighing mechanism, preferably of the following construction.

V is a rock-arm pivoted in the frame and carrying a roll or bearing b, which rests against the arm N in the normal position of the latter.

c is a rod connecting the rock-arm V with 95 a rock-arm d and a rock-shaft e, which carries the guard U.

f is a spring connected with the rod c and adapted to actuate the same in a direction to rock the shaft e and withdraw the guard U 100 from the slot U'. This movement is, however, prevented so long as the arm N is held in its normal position and bears against the roll b on the rock-arm V. When a weight is placed on the platform, the actuation of the 105 arm N through the mechanism before described will withdraw it from contact with the roll b on the rock-arm V, permitting the latter to move under the actuation of the spring f, which will cause the withdrawal of 110 the guard from the slot.

The machine being constructed as shown and described the general operation is as follows: An operator desiring to ascertain his weight first steps upon the platform A. 115 This will immediately cause the actuation of the steelyard-rod E, which will draw the cross-head I downward against the tension of the springs J and will simultaneously actuate the rod P' and rack-bar P. The latter through 120 its engagement with the pinion O will swing the stop-arm N until a balance is reached. During this part of the operation all the parts of the mechanism are free to move, so that an exact balance is obtained and the stop-arm 125 N' N is positioned in exact accordance thereto. The movement of the stop-arm will withdraw the guard U, as has been already described, and will permit the operator to insert the coin through the slot into the chute R. When 130

inserted, the coin will pass downward in the chute until it strikes against the latch-arm Q. The impact will be sufficient to disengage said arm from the lug Q', which will permit 5 the weight S² to actuate the arm M' through the medium of the connection S' and segment S². The arm M' will travel slowly, due to the retarding effect of the liquid in the dash-pot S³ and will finally be arrested by the finger 10 a striking against the stop-arm N. In the initial movement of the arm M' the cam S⁴ will travel in relation to the roll T⁶ on the arm T⁵, so as to permit said arm to be moved in the direction of the arrow. The movement 15 is caused by the weight P⁵, which draws downward upon the link T, rocking the arms T² and T³, and draws upon the link T⁴, which is connected to the rock-arm T⁵. As soon as the arm P⁴ descends it will tilt the dog P³ and 20 cause it to lock the rod P'. This will prevent further movement of the arm N, so that the striking of the finger a against said arm will not displace it from the position assumed in balancing the weight. The indication of the 25 correct weight is given by the index M in connection with the scale indications on the casing. As shown, these indications are preferably arranged on a segmental plate W, which is arranged in rear of a slot or transparent 30 window W' in the casing, and the index M is preferably bent to travel in front of the segment, as shown in Fig. 2.

When the weight is removed from the platform, the cross-bar I will be lifted by the 35 springs J and will cause the upward travel of the rod P' and rack-bar P, while the latter through the pinion O will return the stop-arm N to its normal position. The upward movement of the rod P' is permitted, by reason of the fact that the dog P³ only locks said 40 rod from downward movement. During upward movement any binding of the dog upon the rod is instantly relieved by the lifting of the weighted extension P⁴. The returning 45 stop-arm N will carry with it the arm M' and index M, and as soon as the arm M' is returned the latch-arm Q will reengage with the lug Q', so as to lock the index until again released by the coin. The stop-arm N will also strike 50 against the roller b on the rock-arm V and actuate the latter, so as to again move the guard U into the slot U' and prevent the insertion of the coin. The dog P³ is moved into releasing position by the reengagement of the cam S⁴ with the roller T⁶ on the arm T⁵, and thus 55 the parts are all restored to normal position automatically.

What I claim as my invention is—

1. The combination of a freely-operable 60 weighing mechanism and indicator, means for preventing the weighing indication during the movement of said mechanism in determining the weight, and means for automatically operating in advance of indication for locking said mechanism, said last-mentioned means

being operable only upon the movement of said indicator.

2. The combination of a freely-operable weighing mechanism, an indicator inoperable during the initial movement of said mechanism in obtaining a balance, means for subsequently releasing said indicator, and means automatically operating in advance of indication for locking said mechanism, said last-mentioned means being operable by the initial 70 movement of the indicator.

3. The combination with a freely-operable weighing mechanism, of a movable stop carried thereby, an indicator provided with independent actuating means for causing it to 80 follow said stop, and normally locked from movement, means for releasing said indicator operable subsequent to the movement of said stop, and means operable upon the initial movement of the indicator for automatically 85 locking said mechanism in advance of the arrest of said indicator by said stop.

4. The combination with a weighing mechanism freely movable to obtain a balance, an indicator locked from operation, means for 90 releasing said indicator and a friction-lock for said weighing mechanism operated by the indicator upon its release.

5. The combination with a weighing mechanism freely operable to obtain a balance, of 95 a reciprocating rod, a stop-arm operatively associated with said reciprocating rod, an indicator having independent actuating means for causing it to follow said stop, and normally locked from movement, a friction-dog for engaging with said reciprocating rod normally held in releasing position, means for releasing said indicator and for causing the engagement of said friction-dog, after the release of the 100 indicator.

6. The combination with a weighing mechanism freely operable to obtain a balance, of 105 a stop-arm pivoted to swing in a segment, an intermediate actuating mechanism between said weighing mechanism, and said stop-arm comprising a rack, and pinion, and a reciprocating rod and friction-dog embracing said rod, and normally held out of binding contact therewith, an indicator adapted to travel in a path adjacent to the path of said stop-arm until arrested by the latter, but normally locked from movement, means for releasing said indicator subsequent to the movement of said stop-arm, and means automatically operating upon the initial movement of the indicator for 110 causing the binding of said friction-dog upon the release of said indicator.

7. The combination with a weighing mechanism of a stop-arm actuated thereby, a normally locked indicator adapted when released 115 to move until arrested by said stop-arm, a segment connected with said indicator, an actuated weight connected with said segment by a flexible connection, a lock for said weighing mechanism, means for releasing said indicator 120

tor, and a cam on said segment for actuating said lock for the weighing mechanism upon the initial movement of said indicator.

8. The combination with a weighing mechanism, of a stop-arm actuated thereby, a normally locked indicator adapted when released to move until arrested by said stop-arm, a lock for said weighing mechanism, a segment on the indicator, and a cam associated with said segment for actuating said lock upon the initial movement of the indicator.

9. The combination with a weighing mechanism, of a movable stop-arm actuated thereby, a normally locked indicator adapted when released to move until arrested by said stop-arm, and cam-actuated means associated with the indicator to lock said stop-arm upon the initial movement of the indicator.

10. The combination with a weighing mechanism, of a stop-arm actuated thereby and pivoted to swing in a segment, a normally locked indicator pivoted to swing until arrested by said stop-arm, means for releasing the indicator, and means operable upon the initial movement of the indicator for locking said stop-arm in its adjusted position.

11. The combination with a weighing mechanism, of a stop-arm actuated thereby and pivoted to swing in a segment, a normally locked indicator pivoted to swing until arrested by said stop-arm, means for releasing the indicator, means operable by the initial movement of the indicator for locking said stop-arm in its adjusted position, and automatic means for returning the indicator and stop-arm to their initial positions.

12. In a coin-controlled machine, the combination with a weighing mechanism, of an indicator normally locked from movement, a

movable stop-arm for the indicator, a reciprocating rod, a rack-and-pinion connection between the rod and movable stop-arm, means for releasing the indicator, and a lock arranged to engage said rod and lock the stop-arm in its adjusted position in advance of the indication.

13. In a coin-controlled weighing mechanism, an indicator normally locked from movement, a movable stop-arm for the indicator, a reciprocating rod, a rack-and-pinion connection between the rod and movable stop-arm, means for releasing the indicator upon the release of the coin, and a friction-lock arranged to automatically engage said rod and lock the stop-arm in its adjusted position prior to the indication.

14. The combination of a freely-operable weighing mechanism and indicator, means for preventing the weighing indication during the movement of said mechanism in determining the weight, and means for automatically operating in advance of the indication for locking said mechanism, said last-mentioned means being operated by the indicator.

15. The combination of a freely-operable weighing mechanism, an indicator operable during the initial movement of said mechanism in obtaining a balance, means for subsequently releasing said indicator, means automatically operating in advance of indication for locking said mechanism, said last-mentioned means being operated by the indicator.

In testimony whereof I affix my signature in presence of two witnesses.

AUGUSTE ARTHUR CAILLE.
